US0D1031620S

(12) **United States Design Patent** (10) Patent No.: **US D1,031,620 S**
(45) Date of Patent: ** Jun. 18, 2024

(54) **ARMREST FOR TRACTORS**

(71) Applicant: **KUBOTA CORPORATION**, Osaka (JP)

(72) Inventors: **Wataru Sasaki**, Osaka (JP); **Gen Futagami**, Osaka (JP)

(73) Assignee: **KUBOTA CORPORATION**, Osaka (JP)

(**) Term: **15 Years**

(21) Appl. No.: **29/835,564**

(22) Filed: **Apr. 20, 2022**

Related U.S. Application Data

(62) Division of application No. 35/510,349, filed on Mar. 16, 2020 (U.S. filing date under 35 U.S.C. 384), and having an international filing date of Mar. 16, 2020, now Pat. No. Des. 953,966.

(30) **Foreign Application Priority Data**

Nov. 8, 2019 (JP) 2019-024901
Nov. 8, 2019 (JP) 2019-024902

(51) **LOC (14) Cl.** **12-16**

(52) **U.S. Cl.**

USPC **D12/421**

(58) **Field of Classification Search**

USPC D12/192, 415, 521-424, 421; D15/17,
D15/28

CPC A01D 67/04; B60N 2/773; B60N 2/38;
B60N 2/797; B60N 2/753
